UNITED STATES PATENT OFFICE.

WILLIAM BUGG MEACHAM, OF BOYDTON, VIRGINIA.

AXLE SKEIN AND BOX.

SPECIFICATION forming part of Letters Patent No. 311,774, dated February 3, 1885.

Application filed June 5, 1884. (No model.)

To all whom it may concern:

Be it known that I, WILLIAM BUGG MEACHAM, a citizen of the United States, residing at Boydton, in the county of Mecklenburg and 5 State of Virginia, have invented certain new and useful Improvements in Axle Skeins and Boxes for Vehicles, of which the following is a description.

Figure 1 is a side view of the axle with its 10 box in section. Fig. 2 is a vertical longitudinal section of the axle and skein. Fig. 3 is a plan view of the metal section B. Figs. 4 and 5 are details of the parts D and f.

The object of my invention is to reduce the 15 friction and facilitate the lubrication of vehicle-axle bearings, and to improve and strengthen the same, as will be hereinafter more fully described.

In the drawings, A represents the axle, 20 which for wagons, carts, &c., is preferably made of wood, but which may in some cases be made of metal. The under side of this axle-arm is recessed or cut away to about half its thickness, and the recess extends back under 25 the axle beyond the axle-arm. In this recessed place is fitted a metal section, B, which completes the outline of the axle-arm and the outer end of the axle. This metal section and the axle are held together by the following means: At 30 the outer end of the metal section is formed an undercut flange, a, with ears or lugs b b on each side of the same, and under this flange, and between the lugs b b, the end of the axle is fitted to prevent lateral displacement. At the 35 back end the metal section B is provided on its inner face with the projections c, which enter holes in the axle and prevent lateral displacement at that end, while a stout clip or metal strap, C, passes around the metal section B and 40 clamps it to the axle and to the metal cap-plate D above, the said metal strap being secured by screw-nuts underneath, as shown. This upper plate, D, is provided with projections d, which fit into holes in the top of the 45 axle to prevent lateral displacement, and said plate extends over the top of the axle a greater distance than the section B does underneath it, so as to cause said upper plate, D, to shoulder upon the full thickness of the axle, and 50 thus impart greater strength to the arm. To

the lower metal section, B, there is cast, or with it is formed in one piece, a flange, B', which fits against the end of the axle at the inner end of the arm and forms a metal bearing. In the lower side of the metal section B is formed a longitudinal channel, in which there is arranged in bearings the revolving skein S, which has two bearings, e e, upon the axle-box. This revolving skein has its outer end fitted in a socket in the outer end of the section B, and its inner end is retained by a plate, f, clamped by strap C, which plate f also forms a sand-guard.

For lubricating this revolving skein, several holes, g g g, extend through the metal section 65 B and conduct oil from the longitudinal channel h in the upper face of the section B to the bearings of the revolving skein. This channel h communicates through a perforated rubber block, i, with an oil-reservoir, j, in the 70 upper face of section B. Around this reservoir and along the sides of the channel h is a raised flange or wall, k, which, when the section B is tightly clamped against the axle, forms an oil-tight joint. In the upper cap-plate, D, is formed an oil-cup, l, having an 75 opening in the bottom that registers with a hole, m, through the axle, leading to the oil-reservoir j. This oil-cup l has a screw-threaded cover, m, to keep out dust and dirt.

To regulate the flow of oil from the reservoir to the skein-bearings, a set-screw, n, is tapped through the metal section B of the axle, and is made to bear against a steel plate, o, which in turn bears against the perforated 85 rubber block i, so that by turning this set-screw in or out the size of the hole in the same and the flow of oil therethrough may be increased or diminished.

E is the upper metal skein-bearing of the 90 axle-arm. This is in the nature of a strip of metal inserted under the metal flange at the outer end of the arm, and having at its inner end an upturned portion, p, that enters a hole or recess in the flange d of cap-plate D, and 95 by which it is held in place in connection with one or more screws passing through it into the axle-arm.

F is the axle-box, which is in the nature of a tapering metal sleeve having a flange, q, at 100

its large end and ribs *r* to tightly hold it in the hub against turning. The outer end of this axle-box is screw-threaded a short distance, and after it is inserted and driven into the hub a screw-collar, *s*, with notches for a wrench, is turned upon the same so as to clamp the hub between it and the flange *q* at the other end, thus tightly holding the box to the hub without the necessity of wedging. To prevent the screw-flange from being accidentally turned off by friction of the wheel in revolving, the direction of the screw-thread is such that it has to be turned in the opposite direction to that of the wheel to take it off.

Having thus described my invention, what I claim as new is—

1. The combination, with an axle having its arm cut away on its under side, of a metal section, *B*, having overhanging flange *a*, the cap-plate *D*, and the strap or clip *C*, as and for the purpose described.

2. The combination, with the axle, of the metal section *B*, having overhanging flange *a*, the metal strip *E*, having upturned end *p*, the plate *D*, having a recess to receive said upturned end, and the metal strap *C*, as and for the purpose described.

3. The combination, with the axle having oil-hole *m*, of the plate *D*, having oil-cup *l*, the metal section *B*, having oil-reservoir *j*, chan-

nels *h* and *g*, and the revolving skein *S*, as and for the purpose described.

4. The metal section *B*, having oil-reservoir *j* and channel *h*, with a raised wall or rib around the same, in combination with the axle 35 and means for holding them together, as described.

5. The combination, with the metal section *B*, of the revolving skein *S* and the retaining-plate *f* and means for clamping it to the sec- 40 tion *B*, substantially as described.

6. The combination, with an axle-arm having therein an oil-reservoir and distributing-channels, of a perforated rubber block interposed between the reservoir and channels, and 45 a set-screw for varying the size of the hole in the rubber block to regulate the admission of oil, substantially as shown and described.

7. The metal section *B*, having flange *B'*, in combination with the axle, the cap *D*, having 50 flange *d* fitting down upon *B'*, and the strap *C*, as shown and described.

The above specification of my invention signed by me in the presence of two subscribing witnesses.

WILLIAM BUGG MEACHAM.
